PRESSURE HINGED LEVER SYSTEM FOR CYLINDERS OF SLIVER OR LAP DRAWING FRAMES FOR USE IN SPINNING TEXTILE FIBERS OF VARIOUS KINDS

Luigi Marzoli, Palazzolo sull' Oglio, Italy; vested in the Alien Property Custodian

Application May 22, 1941, Serial No. 394,670
In Italy June 3, 1940

6 Claims. (Cl. 19—135)

In the drawing frames of various types heretofore known the top or pressure cylinders are pressed on the lower cylinders under a direct pressure produced by a weight carried by a hooked rod connected to the side bushes of each cylinder. In this arrangement a weight is required for each cylinder line and each cylinder head. This weight in the sliver drawing frame now in use is of about 9 kilos. Eight of these weights being required for each head, each head is weighted with about 72 kilos.

It has been proposed to reduce the weight by using a lever for each couple of cylinders and therefore four weights of considerable size for each cylinder group.

The object of this invention is to reduce substantially the weight of the pressure members in order to reduce the cost of manufacture and obtain an easier control of the pressure on the drawing cylinders.

According to this invention the pressure on each cylinder group is obtained by means of two small weights, each of about 2.50 kilos acting on the top cylinders through a system of multiplying levers.

Each end of the groups of drawing cylinders is provided with crosspieces bearing on the supporting bushes of the couples of top cylinders. The crosspieces are connected with tie-rods swivelled on the ends of a rocker arm centrally pivoted to a fork connected to the lever fulcrumed at its end, near to the fork attachment, to a fixed part of the machine and carrying at its other end a weight, the lever arm of which may be adjusted according to the desired pressure.

The weights can be raised at will by means of eccentrics connected together by means of a hinged lever system and operated by a central operating member; the sliver or lap is thus released from the pressure of the top cylinder through an easy and simple operation.

The annexed drawings show by way of example an embodiment of the invention.

Fig. 1 is a side view partially sectioned,

Fig. 2 is a cross section,

Fig. 3 is a diagrammatic perspective view,

Fig. 4 is a diagrammatic perspective view of a detail of the weight raising lever system.

Referring to the drawings, 1 is the drawing frame, on which are fitted on fixed bearings the groups of couples of lower drawing cylinders 2. A top cylinder 3 rotatably mounted on vertically movable end bushes 4 cooperates with each of the lower cylinders. A crosspiece 5 carrying a tie rod 6 rests on the adjacent bushes of each couple of top cylinders. The lower end of the tie rod 6 is hinged to the end of a rocker arm 7 centrally pivoted on the forked head of a screw 8 anchored to a lever 9 of the second order near its

fulcrum or pivot 10, by means of which the lever is hinged to the drawing frame.

A weight 11 is hung to the free end of the lever 9; the position of the weight may be adjusted by displacing the hook 12 along the lever 9, which is provided with a plurality of holes 13, in which may be fitted the pin receiving the hook. It is thus possible to adjust the pressure according to the nature of the fiber to be treated.

10 The lower side of each lever 9 is provided with a cam surface 14 cooperating with an eccentric drum 15 pivoted to brackets 16 fixed to the drawing frame. The eccentric drums are connected together by means of the hinged lever system 17, so that they move through the same angle of rotation and are operated simultaneously by means of a handle 18 keyed on a shaft 19 mounted at one end of the drawing frame and connected by means of an arm 21 and rods 22 to the hinged lever system 17.

15 In the example shown each group of drawing cylinders comprises two adjacent couples of lower cylinders coacting with two adjacent couples of top cylinders. The lever provided with a weight acting on one end of each couple of top cylinders is oppositely directed with respect to the lever acting on the other end of said couples and is arranged on one side of the latter, so that the same eccentric drum acts on both levers; the 20 cylinders are thus displaced parallel to themselves.

25 What I claim is:

1. In a lap drawing frame for spinning textile fibers having cooperating top and bottom cylinders which are rotatably supported one above the other with each top cylinder being vertically movable and force applying means associated with the ends of each top cylinder for transmitting a downwardly directed force thereto whereby to move each top cylinder into pressure contact with its cooperating bottom cylinder, the combination of lever means connected to said force applying means for exerting pressure on the cylinders, said lever means comprising levers carried by said lap drawing frame, each lever being fulcrumed at one of its ends on said frame below said cylinders and being connected between its fulcrum and its free end to one of said force applying means; the levers in a pair of levers extending in opposite directions and towards each other from their fulcrums and having their free ends located below the cylinders, said levers lying in substantially vertical planes which are substantially parallel to the longitudinal axes of said cylinders.

2. In a lap drawing frame for spinning textile fibers, cooperating top and bottom cylinders which are rotatably supported one above the other, each top cylinder being also supported for vertical movement, force applying means associated with each end of each top cylinder for

transmitting a downwardly directed force thereto whereby to move each top cylinder into pressure contact with its cooperating bottom cylinder, pairs of levers carried by said drawing frame, each lever being fulcrumed at one of its ends on said drawing frame at a position below said cylinders, means connecting each lever of a pair of levers between its fulcrum and its free end to one of said force applying means for transmitting a force to the force applying means to which the lever is connected when downwardly acting pressure is exerted on the lever, the free end of each lever being located below said cylinders, said levers in each pair extending in opposite directions and towards each other from their respective fulcrums and lying in planes which are substantially parallel to the longitudinal axes of said cylinders, means for exerting downwardly acting pressure on the free end of each lever, and means carried by the frame in contact with each lever for raising the levers against the action of the means exerting pressure thereon whereby to relieve the cylinders from pressure contact.

3. In a lap drawing frame for spinning textile fabrics, cooperating top and bottom cylinders which are rotatably supported one above the other, each top cylinder being also supported for vertical movement, force applying means associated with each end of each top cylinder for transmitting a downwardly directed force thereto whereby to move each top cylinder into pressure contact with its cooperating bottom cylinder, pairs of levers carried by said drawing frame, each lever being fulcrumed at one of its ends on said frame at a position below said cylinders and having its free end located below the cylinders, means connecting each lever of a pair of levers between its fulcrum and its free end to one of said force applying means for transmitting a force to the force applying means to which the lever is connected when downwardly acting pressure is exerted on the lever, the levers in each pair extending in opposite directions towards each other from their respective fulcrums, means for exerting downwardly acting pressure on the free end of each lever, a drum eccentrically and rotatably mounted on said drawing frame below each pair of levers and in contact therewith, and actuating means for rotating each drum whereby to raise and lower said levers at will.

4. In a lap drawing frame for spinning textile fibers, aligned groups of cooperating top and bottom cylinders, support means for rotatably mounting said cylinders whereby each top cylinder is supported over a bottom cylinder, each top cylinder being also supported for vertical movement, force applying means associated with each end of each top cylinder for transmitting a downwardly directed force thereto whereby to move each top cylinder into pressure contact with its cooperating bottom cylinder, a pair of levers for each group of cylinders, said levers being carried by said drawing frame, each lever of each pair being fulcrumed at one of its ends at a position below and near an end of the group of cylinders with which it is associated and having its free end located below the opposite end of the group of cylinders with which it is associated, means connecting each lever for each group of cylinders between its fulcrum and its free end to one of said force applying means associated

with said group whereby to transmit a force to said force applying means to which the lever is connected when downwardly acting pressure is exerted on the lever, the levers for each group of cylinders extending in opposite directions and towards each other from their respective fulcrums, means for exerting downwardly acting pressure on the free end of each lever, an eccentrically and rotatably mounted drum carried by the drawing frame below and in contact with the levers for each group of cylinders and a lever system hinged to said drawing frame and connected to each drum for simultaneously turning said drums whereby to raise and lower the levers connected to said groups of cylinders.

5. In a sliver or lap drawing frame for spinning textile fibers of various kinds, two pairs of lower cylinders, fixed supports for said lower cylinders, two pairs of top cylinders arranged for cooperation with said lower cylinders, vertically movable supporting end bushings for said top cylinders, cross pieces each resting on a pair of adjacent end bushings, a separate fork located under opposite ends of each pair of said cylinders, a rocker arm for each fork, each rocker arm being pivoted intermediate its end to a separate fork, a plurality of pairs of stirrups, one stirrup of each pair connecting an end of a rocker arm with an intermediate portion of one of said cross pieces, a first pressure lever and a second pressure lever each connected near its fulcrum to a separate fork, each pressure lever being fulcrumed at one end on said frame at a position below said cylinders and having its free end located below the cylinders, the second pressure lever having its free end extending towards and in a direction opposite to that of said first pressure lever, movable weights on the free ends of said pressure levers, and means acting on said levers for raising at will said weights and for releasing the pressure produced by said weights on said top cylinders.

6. In a sliver or lap drawing frame for spinning textile fibers of various kinds, two pairs of lower cylinders, fixed supports for said lower cylinders, two pairs of top cylinders arranged for cooperation with said lower cylinders, vertically movable supporting end bushings for said top cylinders, cross pieces each resting on a pair of adjacent end bushings, a separate fork located under opposite ends of each pair of said cylinders, a rocker arm pivoted intermediate its end to a separate fork, a plurality of pairs of stirrups, one stirrup of each pair connecting an end of a rocker arm with an intermediate portion of one of said cross pieces, a first pressure lever and a second pressure lever each connected near its fulcrum to a separate fork, each pressure lever being fulcrumed at one end on said frame at a position below said cylinders, the second pressure lever having its free end extending towards and in a direction opposite to that of said first pressure lever, and said pressure levers having their respective free ends located below said cylinders, movable weights on the free ends of said pressure levers, a drum eccentrically and rotatably mounted on said frame below and in contact with said levers, and a hinged lever system for rotating said eccentric drum for the purpose of raising said weights.
